ATTACHMENT FOR TYPE CASTING
MACHINES

Joe V. Whitmer, Los Angeles, Calif.

Application March 9, 1934, Serial No. 714,785

1 Claim. (Cl. 199—52)

My invention relates to type casting machines wherein a line of type is formed by setting up a series of matrices which are passed in the machine to molding apparatus in which molten type metal is forced into the matrices to cast a slug of corresponding type and in which such slug of type is ejected from the molding apparatus of the machine by an automatically operated ejector including a number of slender ejector blades which are adapted to enter between the liner or lining of the molding apparatus. In such machines the molding apparatus is provided with a plurality of mold blocks mounted upon a circular mold member so that any one of these mold blocks may be employed to cast the slug of type. Each of these mold blocks may be provided with liners determining the length and width of the slug to be cast therein and when any one of these molds is used for casting a slug of type, the ejector must be set to select a number of ejector blades corresponding to the length of the slug determined by the liners in the molding blocks. It is frequently necessary for the operator to change the length of the slug to be cast, this is accomplished by pulling the mold disc turning pinion forward and turning the mold disc to bring the proper length mold into casting position, it is then necessary to reset the ejector blade to correspond to the length of slug to be cast in order to avoid damage to the liner or ejector blades.

Should the operator fail to reset the ejector to correspond with the length of slug for which the newly selected mold is lined, it will be apparent that on the next molding operation the ejector blades would either damage the liner of the newly selected molds or the ejector blades themselves would become damaged.

It is, therefore, an object of my invention to provide means which will require the operator to reset the ejector blade upon each change or selection of the mold to be used.

Another object of the invention is to provide locking means which will be automatically operated by the movement of some part of the machine employed to select the new mold, to positively lock the machine against further delivery of lines of matrices until the operator has reset the ejector blades to correspond to the newly selected mold.

Changes in the form, proportions and minor details of construction may be made within the scope of the claim without departing from the spirit of the invention.

Other objects, advantages and features of in-

vention may appear from the accompanying drawings, the subjoined detailed description and the appended claim.

The accompanying drawings illustrate the invention.

Figure 1 is a perspective view of a portion of a type casting machine, illustrating my locking means attached thereto;

Figure 2 is a detail, perspective view of my locking means, illustrating the normal position of the locking means disengaged from the assembling elevator mechanism of the machine; and

Figure 3 is a perspective view, similar to Fig. 2, illustrating the manner in which my locking means locks the assembling elevator against movement until the ejector mechanism has been reset.

Figure 4 is a fragmental diagrammatic view showing the lock lever extension in locked position with the assembling elevator.

Figure 5 is a view analogous to Fig. 4 showing a side elevation.

Figure 6 is an enlarged fragmental detail view of the bracket showing how the spring is fixed thereto.

Referring to the drawings, I have illustrated in Fig. 1 a portion of a type casting machine 1, the particular machine illustrated herein being known as the "Linotype" machine, as a typical example of a machine to which my invention is adapted. This machine includes, generally, a keyboard A which when actuated will select matrices from a magazine, not shown, and which matrices will fall through a matrix chute B into a "stick" 35 or assembling elevator C. The assembling elevator fills itself and is manually raised or elevated by means of a handle D connected by a shaft E and an elevating lever F to a rod G which attaches to the lower end of the assembling elevator C. The upward movement of assembling elevator C delivers the assembled matrices to the delivery slide H where the assembled matrices are automatically, and without any further attention on the part of the operator, carried to 45 a mold disk K where molten metal is forced into the matrices to cast a slug of type corresponding to the assembled matrices. The mold disk K includes a plurality of mold blocks L, M, N and O, any one of which may be selected for the particular size type to be cast and for the particular length of line or slug which is to be cast. Each of the mold blocks L, M, N and O is provided with suitable liners, not shown, by which the particular mold block is adjusted to fit the desired thick- 55

ness and length of line. The mold disk K is turned to locate the selected block in the right-hand position on the disk K and the automatic portions of the machine will hold the disk K in this position until the molding operation is to take place, and then will cause the mold disk K to rotate through 90° to place the mold block in the casting position. After the slug has been cast, the disk is automatically rotated through 270° back to the initial position, where the block is aligned with an ejector P. The ejector P moves forwardly and rearwardly of the machine to press a plurality of ejector blades Q through the mold disk K and the selected block to press the cast slug out of the mold block. The ejector P is provided with an adjustable mechanism for selecting the number of ejector blades which will be moved forwardly by movement of the ejector, such adjusting mechanism including a handle R connected by means of a lever S pivoted at T, the opposite end U of the lever being connected to a vertically movable upright V attached by means of a rod W to an adjusting slide X so that movement of the handle R will cause the adjusting slide X to move upwardly or downwardly in the ejector P to permit a selected group of ejector blades Q to be moved into and through the selected mold block.

When the size of type or length of line is to be changed, the operator grasps a handle Y connected to a pinion Z and draws this pinion forwardly into engagement with the teeth on the exterior of the mold disk K, turning this mold disk K by hand to bring any one of the other mold blocks M, N or O into vertical position, and thereafter the automatic operation of the machine will cause this newly selected mold block to be used for the molding of the new length or width of line of type. This newly selected block then moves through the various positions, ending with the location of this newly selected block adjacent the ejector. When such adjustment or selection of the new mold block is made, it is necessary that the ejector P be readjusted to select a different number of ejector blades Q to fit the particular length of this newly selected mold block and the operator makes this adjustment by appropriate movement of the handle R.

In order to insure that the operator of the machine will readjust the ejector each time he makes a new selection of molding block, I provide locking mechanism which is actuated by the movement of the pinion Z in making such new selection, the locking mechanism engaging some part of the machine which will prevent the start of the automatic molding cycle of the machine on a new line until such adjustment has been made. This locking mechanism may comprise a horizontal shaft I disposed transversely across the machine immediately below the molding disk K.

The left-hand end of the shaft I is supported in a bearing 2 formed upon a bracket 3 attached to the frame or stand 4 of the machine, near the left-hand side thereof. Near the left-hand end of the shaft I, I secure an upwardly extending lever 5, the extreme upper end of which is bent rearwardly to form a finger 6 engaging the front face of the pinion Z. The lever 5 is rigidly secured to the shaft by means of a suitable set screw 7 so that when the pinion Z is moved outwardly by the operator in making a selection of a new molding block, the pinion lever 5 will be moved outwardly and will cause a partial rotation 75 of the shaft I.

The opposite or right-hand end of the shaft I is supported upon a bracket 8 secured to the frame or stand 4 of the machine by means of bolts 9, the bracket 8 being provided with a forwardly extending web 10 through which the shaft I extends and in which the shaft I may be rotated. Rigidly secured to the shaft I, near its right-hand end, is a lock lever 11 which has a forwardly and upwardly extending arm 12 thereon, the upper end of which is bent forwardly in the shape of a hook 13 disposed immediately at the rear of the inner end of the assembling elevator operating lever F. Thus every time the pinion Z is drawn forwardly to make an adjustment or a new selection of the molding blocks, the hooked end of the lock lever arm 12 will engage above the assembling elevator operating lever and prevent upward movement of the assembling elevator until the lock lever is released therefrom.

Near the upper end of the bracket 8, I form a vertical slot 14 in the web 10 in which slot operates a latch lever 15, the right-hand end of which is pivoted upon the bracket 8 at 16. The left-hand end of the latch lever 15 is provided with an adjustable extension 17 formed as an inverted L-shaped member, the vertical leg of which is clamped in a slot 18 in the end of the latch lever 15 by means of a suitable clamping screw 19. The length of the latch lever 15 and its extension 17 is such as to dispose the outer end of the extension 17 immediately above and in the path of movement of the operating lever S for the adjustment of the ejector blades Q so that whenever the operating lever S is moved by the operator to make an adjustment of the number of ejector blades Q the movement of the lever S will lift the latch lever 15 to the desired position shown in Fig. 2 of the drawings.

The lock lever 11 is normally in its rearmost position, as shown in Figs. 1 and 2, with the hooked end 13 of the lock lever arm 12 disengaged from the operating lever for the assembling elevator and when the lock lever is in this position, a locking screw 20 threaded through the lock lever 11 has its head 21 disposed immediately below the latch lever 15, holding the latch lever 15 in its elevated position, as shown in Fig. 2.

However, when the pinion Z has been moved forwardly in making a new selection of the molding block, and has moved the locking lever 11 and its arm 12 forwardly into hooked locking engagement with the assembling elevator operating lever F, the forward movement of the lock lever 11 will move the head 21 of the locking screw 20 out from under the latch lever 15, allowing the latch lever 15 to descend behind the screw head 21 to the position shown in Fig. 3. The length of the locking screw 20 is selected such that when the latch lever 15 falls down behind the screw head 21, it will hold the lock lever 11 in its forward or locked position until the latch lever is again raised upon a subsequent adjustment of the ejector blades Q.

It will thus be observed that whenever the pinion Z is moved by the operator to select a new or different molding block, the forward movement of the pinion in making this adjustment will cause the assembling elevator C to be locked against upward movement and to remain so locked until a subsequent operation of the ejector adjusting mechanism has been accomplished. When the operator moves the adjusting lever S to make the ejector adjustment, he will first swing the ejector lever handle downwardly 75

to its fullest extent, thus causing the lever **S** to lift the latch lever **15** back to its normal position, as shown in Fig. 2, and then he will proceed to make the adjustment required for the new 5 mold, and a spring **22**, interposed between a forwardly projecting shelf **23** on the web **10** and the lower end of the lock lever **11**, will cause the lock lever **11** to be moved upwardly and rearwardly 10 to the position shown in Fig. 2, thus disengaging the hooked end **13** of the lock lever arm **12** from its locking relation with the assembling elevator.

I prefer to provide a spring **24** to urge the latch lever **15** downwardly, such spring being interposed between the upper surface of the latch lever **15** and a cotter pin **25** extending through the upper end of the bearing web **10** and across the slot **14**.

I also prefer to provide an adjusting screw **26** passing through the lock lever **11** to engage the 20 outer surface of the bearing web **10** to limit the rearward movement of the lock lever **11** and its arm **12**.

As will be understood by those skilled in the art, the locking down of the assembling elevator 25 will prevent the passing of a new stick of matrices into the delivery slide of the machine, and it will also be understood by those skilled in the art that a stick of matrices delivered to the delivery slide starts the automatic molding cycle of operations 30 of the machine. Therefore if the delivery of this new stick of matrices is prevented, there can be no automatic operation of the molding portions of the machine and hence there can be no operation of the ejector **P**. However, by the employment of 35 the locking device hereinbefore described, it will be apparent that the operator of the machine cannot make an adjustment or new selection of a molding block and then inadvertently fail to properly adjust the ejector blades, since until some adjustment of the ejector blades is made, the assembling elevator is locked against movement and against the possibility of delivery of 40 a new stick of matrices to the molding portions of the machine.

Should the operator forget, or fail to make the adjustment of the ejector blades, he will be reminded of his failure as soon as he sets up the next stick of matrices and attempts to operate 45 the assembling elevator handle **D**.

It will therefore be observed that I have provided locking means which will prevent the operator from delivering a new stick of matrices to

the automatic molding portions of the machine until after he has made the necessary adjustment of the ejector blades to fit the new molding block which he has selected and that as soon as he has made the adjustment, such locking means will 5 be released and permit the machine to go through its normal cycle of operations without interruption.

It will also be observed that the construction of my locking means is extremely simple 10 and does not interfere in any way with the usual construction and operation of the machine.

While I have shown and described the preferred embodiment of my invention, it is to be understood that I do not wish to be limited to any 15 of the details of construction, except as defined in the appended claim.

I claim:

In combination with a type casting machine 20 having an assembling elevator in which a plurality of matrices are assembled and having molding apparatus for molding lines of type when said matrices are started into operation by delivery of said matrices from said assembling elevator and having a pinion manually operable 25 by the operator for moving said mold disk to select different ones of said molding blocks and having ejector means for ejecting molded lines of type from said molding blocks, an ejector adjusting lever for adjusting said ejector to correspond to the selected molding blocks, an attachment for said machine including a shaft 30 extending across said machine below said pinion and said assembling elevator, a locking lever secured to said shaft and disposed at the rear of 35 said assembling elevator for movement between a position engaging said assembling elevator and to a position disengaging said assembling elevator, a pinion lever secured to said shaft and extending upwardly into engagement with said 40 pinion, whereby movement of said pinion to make a selection of molding blocks will rotate said shaft and move said locking lever into engagement with said assembling elevator, spring means normally urging said locking means out of engagement with said assembling elevator, latch means for holding said locking means into engaged position when so moved, and means actuated by movement of said ejector adjusting lever for releasing said latch means. 45
